US0D1114013S

(12) **United States Design Patent** (10) **Patent No.:** **US D1,114,013 S**
(45) **Date of Patent:** **** Feb. 17, 2026**

(54) **ROBOTIC DEVICE**

(71) Applicant: **Boston Dynamics, Inc.**, Waltham, MA (US)

(72) Inventor: **Aaron Abroff**, Acton, MA (US)

(73) Assignee: **Boston Dynamics, Inc.**, Waltham, MA (US)

(**) Term: **15 Years**

(21) Appl. No.: **29/921,273**

(22) Filed: **Dec. 15, 2023**

(51) **LOC (15) Cl.** **15-99**

(52) **U.S. Cl.**

USPC **D15/199**

(57) **CLAIM**

The ornamental design for a robotic device, as shown and described.

DESCRIPTION

FIG. 1 is a front perspective view of a first embodiment of a robotic device showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is the top plan view thereof;
FIG. 7 is the bottom plan view thereof;
FIG. 8 is a front perspective view of a second embodiment of a robotic device showing my new design;
FIG. 9 is a front elevation view thereof;
FIG. 10 is a rear elevation view thereof;
FIG. 11 is a right side elevation view thereof;
FIG. 12 is a left side elevation view thereof;
FIG. 13 is the top plan view thereof; and,
FIG. 14 is the bottom plan view thereof.
The broken lines depict portions of the robotic device that form no part of the claimed design.
